UNITED STATES PATENT OFFICE.

EDWARD J. LAWRENCE AND HENRY WHITE, OF FLUSHING, NEW YORK.

LOCKER.

1,076,378.

Specification of Letters Patent.

Patented Oct. 21, 1913.

Application filed September 17, 1912. Serial No. 720,843.

To all whom it may concern:

Be it known that we, EDWARD J. LAWRENCE and HENRY WHITE, citizens of the United States of America, residing at Flushing, in the county of Queens and State of New York, have invented new and useful Improvements in Lockers, of which the following is a specification.

This invention relates to improvements in lockers or cabinets and in the present instance has particular application to a cabinet for use on the exterior of dwellings and in which merchants may place articles of food and the like and lock such articles within the cabinet against theft. It is to be understood, however, that the invention in its useful application is not limited to this particular purpose as the same may be employed wherever it is desired to safely hold articles, such for instance, as clothing and the like.

In carrying out the present invention, it is our purpose to provide a cabinet or locker wherein a plurality of articles may be locked within individual compartments, and wherein articles may be placed in unoccupied compartments without access being had to the occupied compartments.

Furthermore, we aim to provide a cabinet embodying among other features, a casing and a plurality of partitions or division plates mounted within the casing in such manner as to divide the same into non-communicating compartments when it is desired to place articles therein and wherein the partitions may be held in operative or in compartment forming and in inoperative or non-compartment forming positions.

It is also our purpose to provide a cabinet wherein by means of a plurality of movable partitions or division plates the cabinet may be divided into non-communicating compartments when desired and wherein occupied compartments will be rendered inaccessible to unauthorized persons and unoccupied portions of the casing accessible for the placing of articles therein and capable of being formed into compartments.

With the above and other objects in view, the invention consists in the construction, combination and arrangement of parts hereinafter set forth in and falling within the scope of the appended claims.

In the accompanying drawings, Figure 1 is a front elevation of a cabinet constructed in accordance with the present invention,

the doors thereof being shown in open position. Fig. 2 is an end view thereof. Fig. 3 is a vertical sectional view through the same, the division plates being shown in compartment forming position, and Fig. 4 is a perspective view of one of the partitions removed from the cabinet.

In the present instance, we have shown our invention as embodied in a double cabinet, that is, a cabinet embracing two independent casings formed, in this instance, integral with each other and capable of being divided into three non-communicating compartments, but it is to be understood, that the cabinet is not limited to any particular size or capacity, as the same may be formed to provide any number of non-communicating compartments and as many of such cabinets connected to one another, as is desired.

Referring now to the accompanying drawings in detail, each cabinet includes a casing 1 having an open side 2 and an open end or top 3. A door 4 is adapted to close the open side of the casing and this door, in the present instance, is hinged to one wall of the opening and movable about a vertical pivot, it being understood, of course, that the door may be applied to the casing in any suitable manner, a lock 5 being carried by the door to lock the same in closed position. The open end or top of the casing is, in this instance, provided with a hinged cover 6 whereby the top of the casing may be closed against the entrance of dirt, dust and other foreign matter.

In order to divide the casing of the cabinet into non-communicating compartments when such is desired as when placing articles therein, and to permit access to the unoccupied portions of the casing so that such portions may also be divided into compartments without having access to the occupied compartments, we employ a plurality of partitions or division plates 7 which, in the present instance, are of rectangular contour to conform to the cross sectional configuration of the casing and each has one side edge bent upon itself and housing a pivot rod 8 the free ends of the latter being projected beyond the ends of the respective partition and journaled in alining apertures formed in the end walls of the casing adjacent to the closed side thereof, the opposite side edges of the partitions or division plates being bent upon

themselves and housing reinforcing rods 9. These pivot rods 8 form horizontal pivots for the partitions or division plates and are appropriately spaced apart so that the partitions when inoperative or in non-compartment forming position may lie against the adjacent surface of the closed side of the casing, as clearly illustrated in Fig. 3, the partitions, when in non-compartment forming positions, lying in a vertical plane. If, however, it is desired to divide the casing of the cabinet into segregated or non-communicating compartments, the partitions are swung to a horizontal position thereby separating the lower portion of the cabinet from the upper portion thereof. For the purpose of stabilizing or holding the partitions in compartment forming position when thrown to the horizontal, each partition, in the embodiment of our invention selected for illustrative purposes, has formed integral with the opposite end edges thereof downturned wings 10, 10 having straight edges 11 designed to abut the adjacent wall of the casing.

To hold the partitions or division plates in a vertical position so that accidental movement thereof is avoided and to lock such partitions in horizontal position and compartment formation, a suitable form of latching device is employed. In this instance, a spring pressed latching pin 12 is carried by the free edge of each partition approximately centrally thereof and is adapted to engage in an aperture in a lug 13 carried by the closed side of the casing immediately above the side edge of the respective partition thereby holding the division plates in non-compartment forming positions, the pins being disengaged from the lugs when it is desired to swing the partitions to horizontal and engaged in apertures 14 formed in the door 4 and the upper wall of the door opening respectively, the aperture in the upper wall of the door opening receiving the latching pin on the top-most partition. The various parts of the cabinet are provided with ventilating apertures to promote sanitation.

From the foregoing description taken in connection with the accompanying drawings, the construction and manner of employing our invention will be readily apparent. Assuming the cabinet to be utilized for the purpose of holding articles of food and the like and placed on the exterior of a dwelling in a position convenient for the merchant, the partitions 7 are all thrown to a vertical or non-compartment forming position and held in such position against accidental displacement by means of the latching devices. The door 4 is now swung to a closed position and locked therein while access may be had to the interior of the casing by means of the cover 3. The first mer-

chant to reach the cabinet places his wares in the lower portion of the cabinet and releases the lowermost partition or division plate and swings the same to a horizontal position, the latching pin engaging the respective aperture in the door 4 and locking the compartment against access. The second merchant places his merchandise upon the upper surface of the compartment forming partition and moves the next inoperative partition into horizontal or compartment forming position, thus locking the merchandise against theft. The succeeding merchant operates the next partition, the last, in this embodiment of the invention herein shown, the latching pin entering the aperture in the upper end wall of the door opening. Thus, it will be seen that the cabinet is divided into non-communicating compartments each of which is locked against access. To remove the articles from the respective compartments, the door 4 is unlocked and swung to open the respective side of the casing whereby the articles may be removed from the compartments and the partitions swung to a vertical position thereby placing the cabinet in condition for the reception of more articles.

While we have herein shown and described one particular embodiment of our invention by way of illustration, it is to be understood that we do not confine ourselves to the precise details of construction herein described and delineated, as modification and variation may be made within the scope of the claims and without departing from the spirit of the invention. For instance, the partitions or division plates may be pivoted within the casing in any suitable manner and by any preferred means other than that herein shown, while any desired form of latching device may be employed.

We claim:

1. A device of the class described comprising a casing having an open side and end, a door closing said open side and a cover closing said open end thereof, and a plurality of partitions pivoted in said casing and spaced apart vertically and adapted to divide the same into non-communicating compartments, each partition being of a length and width equal to the similar dimensions of the casing.

2. A device of the class described comprising a casing having an open side and end, a door closing said open side and a cover closing the open end thereof, a plurality of partitions pivoted in said casing and spaced apart vertically and adapted to divide the same into non-communicating compartments, each partition being of a length and width equal to the similar dimensions of the casing and means for locking said partitions against movement.

3. A device of the class described comprising

ing a casing having an open side and end, a door closing said open side and a cover closing the open end thereof, a plurality of partitions pivoted in said casing and adapted to 5 divide the same into non-communicating compartments, said partitions being spaced apart vertically and each of a length and width equal to the similar dimensions of the casing and means for holding said partitions

in non-compartment forming positions and 10 in compartment forming positions.

In testimony whereof we affix our signatures in presence of two witnesses.

EDWARD J. LAWRENCE.

HENRY WHITE.
